UNITED STATES PATENT OFFICE.

JAMES H. CANNON, OF LOS ANGELES, CALIFORNIA.

MAKE AND BREAK DEVICE.

Application filed June 8, 1924. Serial No. 718,862.

My present invention is a make-and-break device for electrical circuits, and it is a special object of this invention to provide an automatic interrupter or control device suitable for use in connection with flashing signs or like loads requiring an intermittent flow of current, or requiring a time-controlled variation in the electrical energy supplied thereto.

10 It is an object of this invention to provide a circuit control device adapted to be interposed between a suitable source of current, such as ordinary direct or alternating current, and any translating device whose current is to be interrupted at predetermined regular intervals or for predetermined periods of time; and it is an object of my invention to provide means whereby the periods of energization may be conveniently 20 varied at will.

It is an object of my invention to provide an automatic circuit control device comprising means for intermittently energizing and deenergizing each of two branch circuits, 25 one of the mentioned branch circuits preferably comprising an electro-magnet, in the form of a solenoid placed in series with a quick-break switch operated thereby, and the other branch circuit, intended to include 30 the "load", being provided with a special switch adapted to be opened subsequently to the energizing of said solenoid and adapted to be closed, under certain conditions hereinafter mentioned, by gravity, the intervals 35 between the mentioned openings and closings being subject to control by adjustable devices which may include a dash pot and a hand valve; and a preferred embodiment of 40 my invention may comprise means causing the mentioned load branch circuit to be opened before the solenoid branch circuit is opened, and means whereby the load branch circuit is automatically closed after a predetermined interval of time, before 45 said solenoid branch circuit is closed, the organization referred to being such as to permit an indefinite repetition of the closing and opening operations.

50 It is an object of this invention to provide a circuit control device comprising an electro-magnet through which extends a rod which may comprise or be provided with magnetic material, this rod being connected at one end with one of the relatively movable parts of a dash pot, or its equivalent, and provided also with circuit control

means, and with means, such as a weight, tending to cause the mentioned movable element to advance in a manner permitting a closure of circuits; and a preferred embodiment of my invention may comprise means facilitating the optional introduction of resistance into the solenoid branch circuit, and also a special snap switch suitable for use in said circuit and a special switch suitable for use in the load circuit, these special switches being preferably associated with and operable by movement of the mentioned rod operably connected with a movable element, such as the piston, of a dash pot.

60 Other objects of my invention will appear from the following description of an advantageous embodiment thereof, taken in connection with the appended claim and the accompanying drawings, in which:

Fig. 1 is an elevational view of an organization embodying my invention, parts being shown in section or broken away.

Fig. 2 is an elevational view taken substantially as indicated by the arrows 2-2 of Fig. 1.

Fig. 3 is an elevational view corresponding to Fig. 1, but showing the parts in different relative positions, both of the branch circuits being shown as open.

Fig. 4 is a plan view which may be regarded as taken in the direction of the arrow 4 of Fig. 3, parts being broken away.

Fig. 5 is an enlarged detail view taken in the direction of the arrow 5 of Fig. 2.

Fig. 6 is a wiring diagram hereinafter referred to.

Referring to the details of the specific embodiment of my invention chosen for purposes of illustration, 11 may be a board or plate of insulating material upon which the respective parts of my device may be mounted in a substantially vertical position; and this device may comprise, among its essential parts, a solenoid 12 mounted above a reservoir 13 adapted to contain a liquid such as oil, and a vertically extending rod 14, extending through said solenoid and shown as carrying at its lower end a piston 15, movable within a relatively fixed cylinder 16, the mentioned piston and cylinder functioning as the co-operating parts of a dash pot containing oil, or the like, confined within the receptacle 13.

100 Line wires 17 and 18 may be respectively connected with terminals 19 and 20, from which a "solenoid" branch 21 and a "load"

branch 22 may extend in parallel relationship, a pair of load terminals being shown at 23 and 24. A strip 25, shown as secured by bolts 26, 26', may provide a short connection between the terminals 20 and 24, and a conductive strap 27 may be employed to carry the current from the line terminal 19 across the back of the insulating plate 11 to a post 28, in conductive connection with one of a pair of contact elements 29, 29' in the load branch circuit 22; and the solenoid branch circuit 21 may comprise a wire 30, one end of which may be permanently secured to a fixed contact 31 of a quick-opening switch placed in series with the solenoid 12, a post 32 being shown as provided on the conductive body 33 of said switch to facilitate the connecting therewith of a wire 34, which may be continuous with the mentioned wire 21, optionally employed in the winding of said solenoid. One end of the wire 30 may be secured to a post 35, in such manner as to complete the solenoid branch circuit through a resistance 36, shown as a fine wire guarded by a tube 37 of glass or similar material; or, when this resistance is not required, the wire 30 may optionally be connected to a post 38, the posts 35 and 38 being suitable for employment in supporting the resistance 36 and its protecting tube 37, as by means of conductive brackets 39, 39', through which the solenoid branch circuit is completed when the mentioned resistance is interposed. On the substantially vertical rod 14, which is elevated, whenever the solenoid 12 is energized, in a known manner, by the attraction of magnetic material comprised therein or associated therewith, I may provide means such as stops or tappets 40, 41, preferably formed of or faced with insulating material, to actuate the mentioned quick-opening switch, in series with said solenoid; and this switch may comprise, in addition to the mentioned conductive casting 33, shown as secured by the post 32 and an additional bolt or screw 42, a lever 43, shown as pivoted at 44 on a conductive projection 45, head 46 upon an operating arm of said lever being interposed between the mentioned stops or tappets 40, 41, in such a manner as to swing the conductive arm 47 of said lever through a substantially vertical position, to make and break the circuit through said solenoid. In order to give a snap action or quick-opening movement to a movable contact element 48, mounted upon the distal end of the conductive arm 47, I may employ a movable contact element reduced in diameter at its upper end 49, and provided with shoulders 50 adapted to interfit within arcuate notches 51 provided in parallel walls 52 at the outer end of the arm 47, a resilient element such as the spring 53 being secured at an inter-

mediate point 54 of said arm and also to an intermediate point 55, near the base of a notch extending downwardly from the top of the movable contact element 48. The construction here referred to is such that, when the stop or tappet 41 upon the rod 14 engages the head 46 upon the operating arm of the lever 43, the conductive arm 47 thereof is swung into substantially the position shown in Fig. 3, the contact 48 being thereby snapped, under the action of the spring 53, away from the fixed contact 31 and against a stop 56, shown as secured in the insulating block 57, within which the fixed contact 31 is also secured. An opposite or downward movement of the rod 14, or its equivalent, must obviously be effective to cause engagement of the stop or tappet 40 with the head 46 upon the operating arm of the lever 43, thereby causing an opposite movement of the conductive arm 47 thereof and the sudden remaking of the circuit by an engagement of the movable contact 48 with the fixed contact 31. Obviously, a "load" might be included in this solenoid circuit.

For the making and breaking of the load branch circuit 22, I may employ means comprising a bridging element 58, which may be in the form of a carbon disc conically ground or otherwise formed in the lower portion 59 thereof in such a manner as reliably to form an effective contact with correspondingly tapered or interfitting surfaces upon the mentioned fixed contacts 29, 29', which may be arcuate in plan, although spaced apart at 60 in such manner as to permit a flow of current only when the bridging disc 58, shown as circular in form and surrounding the rod 14, is in contact therewith. The bridging element 58 may advantageously be secured to a sleeve 61, longitudinally movable upon the rod 14, and shown as provided at its upper end with a tapered collar 62, adapted to co-operate with means such as the rollers 63, rotatably mounted upon shafts 64, in the releasable retention of said bridging element in an elevated position. The shafts 64 may be pivoted at 65 upon a bracket 66, adapted to support the same at a fixed level; and the outer ends of these shafts may be resiliently pressed or drawn together, as by means of a spring 67 interposed between the ends thereof, a plate 68, provided with comparatively large apertures 69 being optionally employed to maintain said shafts in substantially parallel relationship, although permitting them to separate sufficiently to allow the collar 62 to pass therebetween.

The rod 14, or its equivalent, may be provided with means constantly tending to force the piston 15 into the cylinder 16, and my preferred means for this purpose may comprise a weight 70 upon the upper end of said

rod, this weight being of insufficient mass to prevent the elevation of the rod 14 when the solenoid 12 is energized, but of sufficient mass to cause said rod to descend when said solenoid is deenergized; and the rate of movement of the rod 14 may be predetermined by means such as a hand controlled needle valve 71, the stem 72 of this valve being shown as provided with a milled head 10 73, above a plate 74, which may serve both as a support for the solenoid 12 and as a cover for the receptacle 13, containing oil or an equivalent fluid. A block 75 may be supported within the receptacle 13 in any suitable way, as by threaded engagement with the lower end of the cylinder 16, and it may be provided with substantially vertical channels 76 and 77 connected by a horizontal channel 78 in such manner that the advancing 20 of the needle valve 71 relatively to a seat 79 may be effective to control the rate of admission or exit of oil past said valve, in response to the lifting effect of the solenoid 12 or the depressing effect of the weight 70. In order to permit adjustment of the rate of descent of the rod 14 without correspondingly retarding the elevation thereof, I may employ means such as a ball valve 80 having a seat 81 at the top of an alternative inlet duct 82. My time-control 30 may be used with either or both switches.

The stop or tappet 40, or its equivalent, may be employed not only to contact, as indicated above, with the head 46 upon the operating arm of the quick-opening switch 35 in series with the solenoid 12, but optionally also to contact with the lower surface of the bridging element 58 in the load branch circuit, to elevate said bridging element; and in order that the elevation of this element shall be completed in such manner as to permit an engagement of the collar 62 and its retention by the rollers 63, or their equivalent, I may mount the lower stop or tappet 45 41 upon the rod 14 in such manner as to permit said rod to slide therethrough until a shoulder 83 on said rod shall engage a washer 84, beneath the stop 41, thereby elevating the same sufficiently to open the solenoid branch circuit only after the collar 62 has passed above the rollers 63. After the 50 solenoid circuit is opened by the actuation of the described quick-opening switch, or its equivalent, in series therewith, the weight 55 70 being effective to depress the rod 14 as rapidly as the adjustment of the valve 71 may permit, the bridging element 58 may

be first released by the pressure of an insulating tappet or enlargement 85, or its equivalent, shown as mounted immediately 60 below said weight, this tappet or enlargement being effective, in its descent, to force the collar 62 through between the rollers 63 and permit the descent of the bridging element 58, falling freely under the action of gravity, into effective contact with the correspondingly ground surfaces of the spaced contacts 29, 29'. Subsequently to the movement just described, the further descent of the tappet 40 may be effective, by engagement of the head 46 upon the operating arm of the quick-opening switch in circuit with the solenoid, to close the circuit through said solenoid and thereby initiate a repetition 70 of the upward movement of the rod 14 and 75 an indefinite repetition of the successive operations referred to.

Although I have herein described one complete embodiment of my invention, it will be understood that various features thereof 80 might be independently employed, and also that various modifications might be made, by those skilled in the art, without the slightest departure from the spirit and scope 85 of my invention, as the same is indicated above and in the following claim.

I claim as my invention:—

In a quick-opening switch operable by means of a reciprocating rod comprised in an automatic make-and-break device, the combination of: a main casting of conductive material; a projection thereon carrying and in conductive contact with a lever; means for securing a conductive lead to said main casting; a fixed contact spaced from said main casting; a contact element mounted on a conductive arm of said lever and movable relative thereto and in conductive contact therewith; and means resiliently connecting an intermediate point of said arm with an intermediate point of said movable contact element in such manner as to assure a sudden separation of said contact elements upon the reciprocation of said rod, the distal end of said conductive arm being provided with parallel notched walls and said movable contact element being provided with a reduced portion extending between said walls and terminated by shoulders extending into said notches. 90 95 100 105 110

In testimony whereof, I have hereunto set my hand at Los Angeles, California, this 2nd day of June, 1924.

JAMES H. CANNON.
